[57] CLAIM

The ornamental design for a gas fired heater, as shown and described.

DESCRIPTION

FIG. 1 is a front perspective view of the gas fired heater;
FIG. 2 is a front elevational view thereof;

FIG. 3 is a front perspective view of the gas fired heater, showing a second embodiment of our new design;

FIG. 4 is a front elevational view of the modified form of FIG. 3;

FIG. 5 is a right side elevational view of the gas fired heater of FIG. 1 and 2, and the modified form of FIGS. 3 and 4;

FIG. 6 is a left side elevational view of the gas fired heater of FIG. 1 and 2, and the modified form of FIGS. 3 and 4;

FIG. 7 is a top plan view of the gas fired heater of FIGS. 1 and 2, and the modified form of FIGS. 3 and 4;

FIG. 8 is an inverted plan view of the gas fired heater of FIGS. 1 and 2, and the modified form of FIGS. 3 and 4; and,

FIG. 9 is a rear elevational view of the gas fired heater of FIGS. 1 and 2, and the modified form of FIGS. 3 and 4.
